UNITED STATES PATENT OFFICE.

FRANK B. ANDERSON, OF CLEVELAND, OHIO.

DESIGN FOR A CASING FOR FILTERS.

41,321.

Specification for Design.

Patented Apr. 18, 1911.

Application filed January 8, 1909. Serial No. 471,370. Term of patent 3½ years.

To all whom it may concern:

Be it known that I, FRANK B. ANDERSON, a citizen of the United States, residing at Cleveland, in the county of Cuyahoga and State of Ohio, have invented a new, original, and ornamental Design for Casings for Filters, of which the following is a specification, reference being had to the accompanying drawings, wherein—

Figure 1 is a top plan view of the casing; and Fig. 2 a side elevation thereof.

The casing may be said to comprise a base 1, substantially cylindrical in form and provided with a swell or enlargement 2 adjacent to the upper edge thereof. A top-piece or cover 3, cylindrical in outline, provided

with a somewhat rounding upper portion or dome 4, and a swell or enlargement 5 at its lower edge, overlies the base 1. A pair of handles 6 extend outwardly from the top-piece or cover 3. The base 1 is formed or provided with vertically-disposed lugs or ears 7, which stand in alinement with similar lugs or ears 8 upon the top-piece or cover 3.

I claim:

The ornamental design for a casing for filters, as shown and described.

FRANK B. ANDERSON.
